Sylvester K. Merrill,
by Edson Salisbury Jones
Attorney.

UNITED STATES PATENT OFFICE.

SYLVESTER K. MERRILL, OF AUBURN, RHODE ISLAND.

DESIGN FOR A GEM-SETTING.

SPECIFICATION forming part of Design No. 14,818, dated February 26, 1884.

Application filed January 17, 1884. Term of patent 3½ years.

To all whom it may concern:

Be it known that I, SYLVESTER K. MERRILL, of Auburn, in the county of Providence and State of Rhode Island, have invented a new and useful Design for Gem-Settings; and I do hereby declare that the following specification, taken in connection with the accompanying drawings, forming a part of the same, is a full, clear, and exact description thereof.

10 This design consists in a gem-setting the face of which is circular in outline or contour, and has a central opening for receiving a brilliant or other stone, which opening is surrounded by a beveled border having its inner 15 edge notched or serrated, as will hereinafter appear.

This design for a gem-setting is particularly adapted for articles of jewelry, such as scarf-pins, ear-drops, studs, &c.

20 In the drawings, Figure 1 illustrates a face view of the setting. Fig. 2 shows the same with a brilliant set in place. Fig. 3 shows a side view and partial section of the setting.

As shown in the several figures, the face of

the setting is circular in contour or outline, 25 and is provided with a central opening, *a*. This opening is surrounded by a beveled border, *b*, the outer edge of which joins the side *c* of the setting. The inner edge, *d*, of the border *b* is notched or serrated, as clearly shown in 30 Fig. 1.

The outer edge of the border *b* may be knurled or beaded, as shown in Fig. 2, or may be plain, as shown in Fig. 1; or the face of the border may be ornamented in any preferred 35 manner, such ornamentation forming no part of the design.

What I claim, and desire to secure by Letters Patent, is—

The design for a gem-setting, having a face 40 which is circular in outline or contour, and a central opening, which is surrounded by a beveled border having its inner edge notched or serrated, substantially as described and shown.

SYLVESTER K. MERRILL.
